Fig. 11

Fig. 12

FIG. 1 is a bottom plan view of the plate for chain door locks showing my new design;
FIG. 2 is a top plan view thereof;

FIG. 3 is an end elevational view thereof;
FIG. 4 is a side elevational view thereof;

FIG. 5 is a bottom plan view of a modified form of the plate for chain door locks described in FIG. 1 showing my new design;

FIG. 6 is a top plan view thereof;
FIG. 7 is an end elevational view thereof;

FIG. 8 is a side elevational view thereof;

FIG. 9 is a bottom plan view of a modified form of the plate for chain door locks described in FIG. 1 showing my new design;

FIG. 10 is a top plan view thereof;
FIG. 11 is a side elevational view thereof;

FIG. 12 is an end elevational view thereof.
The sides and ends opposite to those shown in FIGS. 3 and 4, 7 and 8, and 11 and 12 are identical therewith.

I claim:
The ornamental design for a plate for chain door locks, as shown and described.
